UNITED STATES PATENT OFFICE.

PHILIP C. P. BOOTY, OF CHICAGO, ILLINOIS, ASSIGNOR, BY MESNE ASSIGNMENTS, TO
LESLIE W. FRICKE, OF OAK PARK, ILLINOIS.

POLISHING IMPLEMENT AND POLISHING STRIP THEREFOR.

Application filed July 21, 1922. Serial No. 576,485.

My invention relates to a polishing implement and more particularly to an implement employing a strip of polishing material in which the parts are so arranged that 5 the strip is placed under tension when in use. The implement is specially adapted for manicuring purposes, although I do not intend to limit its use thereto, as I apprehend it may be equally useful for other 10 purposes.

One of the objects of my invention is the provision of a polishing implement so constructed that the strip of polishing material may be conveniently and quickly placed in 15 position on the implement without the necessity of providing any loops or pockets on the ends of the strip, thereby keeping the cost of making the strips down to a minimum and providing a relatively inexpensive 20 arrangement whereby a fresh, clean strip of polishing material may be used for each manicuring or other operation, if desired.

A further object of my invention is the provision of an implement of such construction that the strip of polishing material may be conveniently and quickly placed under the desired tension by the person using 25 the instrument; and, to this end, the invention 30 preferably contemplates a holder provided at one end with an upwardly extending grip portion, means to fasten one end of the strip of polishing material to the end of the holder having said grip portion, and 35 a grip member adjustably mounted on the other end of the holder in combination with means for securing the other end of the 40 polishing strip, the parts being so arranged that when the grip member is moved toward the grip portion, the strip is placed under the desired tension. The grip member is 45 preferably in the form of a lever pivotally mounted on the holder and has associated with it means for securing the adjacent end of the strip of polishing material so that when the lever is rocked on its pivot toward the grip portion provided on the other end of the holder, the fastening means carrying the opposite ends of the strip of polishing 50 material are forced apart, and thus the strip of polishing material may be placed under as much tension as desired.

Another object of my invention is the provision of novel, convenient and effective means for fastening the ends of the polishing strip to the holder; and, to this end, the invention preferably contemplates the provision of a bearing surface on the grip member which is adjustably mounted on one end of the holder and a bearing surface on the 55 other end of the holder in combination with U-shaped clamping members pivotally connected with the holder and the grip member, respectively, so that the medial portions thereof may engage said respective bearing 60 surfaces, the respective ends of the polishing strip being brought into engagement with the bearing surfaces and then passed around the medial portions of the clamping members. 65

A further object of my invention is the provision of a polishing implement so constructed that the holder portion thereof is formed of a plurality of parts hingedly connected and adapted to be folded into 70 compact form when not in use.

A further object of my invention is the provision of novel polishing means for the implement which possesses the desired buffing or polishing characteristics and also has so sufficient strength to resist stretching when it is placed under the tension desired. Chamois has been found to be one of the best materials for producing a high polish on a surface when it is rubbed briskly there-over but chamois, or any other material having the desired characteristics, does not have sufficient strength to enable it to be placed under the necessary tension. In order to overcome this difficulty, I preferably provide a polishing means comprising two strips, one strip being of any desired material adapted to function effectively as a polishing means, for example, a strip of chamois, and the other strip being of some pliable and relatively non-stretchable material, such as cotton or linen cloth, one of the strips having on one side a coating of a cementitious or adhesive substance against which the other strip is pressed to unite the 85 two strips. 90

The invention consists in the novel constructions, arrangements and devices to be hereinafter described and claimed for car-

rying out the above stated objects and such other objects as will appear from the following description of a certain preferred embodiment illustrated in the accompanying drawings, wherein—

Fig. 1 is a perspective view of a polishing implement embodying the principles of my invention;

Fig. 2 is a longitudinal sectional view, on an enlarged scale, of the polishing implement, certain portions thereof being broken out;

Figs. 3 and 4 are sectional views, taken on the lines 3—3 and 4—4, respectively, of Fig. 2; and

Fig. 5 is a perspective view of a preferred form of polishing means for the implement, the two strips comprising the polishing means being pulled apart at one end.

Like characters of reference designate like parts in the several views.

The polishing implement includes a holder in the form of a bar 8 which is provided at one end with a transversely extending head 9, the end and under side of said head being rounded to provide a smooth bearing surface 10 for one end of the polishing strip 11 to bear against. This end of the holder is provided with a grip portion 12 which may be in the form of a ring as shown in Fig. 1. This end of the holder is also provided with means adapted to grip the adjacent end of the strip 11, said means preferably being in the form of a U-shaped clamping member 13 having a transversely extending bar 13 and arms 13^a, the free extremities of said arms being swingingly connected to the head 9 by a pivot pin 14. The distance between the axis of the pin 14 and the extremity of the head 9 is somewhat greater than the distance between the axis of said pin and the bar 13, consequently, when the clamping member is swung downwardly, the medial portion thereof will bear against the upper surface of the head 9. The end of the strip 11 is inserted between the arms 13^a sufficiently so that, when the clamping member is in its lowermost position, the extremity of the strip will be pinched between the lower edge of the transverse bar 13 and the upper surface of the head 9. The main portion of the strip is then brought around over the bar 13 into engagement with the under surface of the head 9.

A gripping member is mounted on the other end of the holder so that it may be adjusted relatively to the holder, said member preferably being in the form of a lever having a head 15 and an upwardly extending grip portion 16, the head straddling the adjacent end of the bar 8 and being swingingly connected thereto by a pivot pin 17. The under side of the head 15 is rounded to provide a bearing surface 18 substantially concentrically disposed with respect to the

pivot pin 17. The head 15 is provided with means to grip the adjacent end of the strip 11, said means preferably being in the form of a U-shaped clamping member having a transversely extending bar 19 and arms 19^a, the free extremities of said arms being swingingly connected to the head 15 by a pivot pin 20. This clamping member operates in the same manner as the clamping member first described. When it is desired to grip the adjacent end of the strip 11, the head 15 is swung around in a clockwise direction and the clamping member attached thereto is swung in an anti-clockwise direction substantially into the position shown in dotted lines in Fig. 2. When the clamping member is in said position, the adjacent end of the strip 11 may be passed around the transverse bar 19 and inserted between the arms 19^a and between the surface 18 and the main part of the strip 11. The head 15 may then be swung around in an anti-clockwise direction which results in the clamping member carried thereby being pulled automatically in a clockwise direction, thereby effectively clamping the end of the strip 11 between the lower edge of the bar 19 and the bearing surface 18.

Since the strip 11 at one end is secured against slippage to the head 9 of the holder and the other end is secured against slippage to the head 15 of the pivotally mounted lever, it will be obvious that, by swinging the lever in an anti-clockwise direction, that is to say, by swinging it so that the grip portion 16 is moved toward the grip portion 12, the strip 11 may be placed under the desired tension. The holder may be gripped in any one of several ways, one convenient way being to pass the ring finger through the ring 12 and bring the thumb of the same hand into engagement with the under side of the grip portion 16. The strip may then be placed under the desired tension, and the holder moved to and fro in the same manner as an ordinary buffer.

It will be noted that the length of the device is approximately equal to the width of one's hand. The device balances nicely in the hand and it is not tiresome to manipulate because the weight of the hand is ample to press the strip against the nail. The construction permits of considerable latitude in fastening the strip to the pivoted lever. If the operator happens to fasten the strip to the lever so that the distance between the two fastening members is less than normal, no difficulty is experienced, because in that case the lever need not be swung quite so far toward the ring to tension the strip. On the other hand, should the strip be placed on the device so that the distance between the two fastening members is greater than normal, the lever is swung a little further toward the ring to tension the strip.

Furthermore, the construction is such that the moment the implement is laid down, the tension on the strip is removed.

- 5 The bar 8, if desired, may be made in two parts 8^a and 8^b, of substantially equal length, the adjacent ends being hingedly connected at 21 in such manner that the parts 8^a and 8^b may be folded to bring one part around against the under side of the other part.
- 10 The hinge 21 is so formed that, when the grip portion 16 is moved toward the grip portion 12, the upper edges of the hinged extremities of the part 8^b abut against the adjacent upper edge of the part 8^a and the parts 8^a and 8^b are brought into rigid relationship, said parts being conveniently held in that relationship because the points at which the parts 12 and 16 are gripped are in a plane considerably above that of 20 the hinge.

The polishing means 11 preferably comprises the strips 22 and 23, the strip 22 being made of some soft pliant polishing material, like chamois, while the strip 23 is 25 made of some strong, pliant relatively non-stretchable material, for example, cotton or linen cloth, the two strips being united preferably by a cementitious substance. I have found that the strips may be inexpensively 30 constructed by using a strip of tape having on one side a coating of adhesive substance and pressing the strip firmly against the strip of chamois. In practice, I prefer to take a relatively large piece of chamois and 35 a piece of strong, pliant non-stretchable fabric material of similar size having on one side a coating of adhesive substance and I unite the two pieces by pressing or ironing them with a hot iron. The adhesive substance unites the non-stretchable fabric material firmly to the chamois, and the pieces may then be cut into strips of the desired 40 length and width.

45 The strip 22 is preferably impregnated with a suitable abrasive substance, for example, crocus powder or rouge. The abrasive substance may be applied to the polishing side of the strip 22 in the form of a powder, but I prefer to dissolve the powder in an alcoholic or other suitable solution and impregnate the under side of the strip therewith.

50 The polishing means is pliable and readily conforms closely to the contour of the nail under slight pressure. It covers a considerable portion of the nail. All tendency for the polishing means to injure the cuticle adjacent the nail, to burn or warp the nail or to cause pain is effectively obviated.

55 The strips are readily removed and placed in position on the holder and, as they are relatively inexpensive, a fresh, unsoiled strip may be used as often as desired. The implement is particularly adapted to meet the 60 needs of the professional manicurist, espe-

cially in those localities where strict laws relating to sanitation are in force and under which the use of an ordinary buffering implement is prohibited. With an implement embodying my invention a fresh, unsoiled strip of the polishing material may be used by the manicurist for each person.

65 I do not intend to limit my invention to the details of construction, arrangements and devices shown and described except only in so far as certain of the appended claims are specifically so limited, as it will be obvious to those skilled in the art that modifications may be made without departing from the spirit of my invention.

70 I claim:

75 1. A device of the class described comprising a holder, a strip of polishing material, means to fasten said strip at one end to one end of said holder, a finger grip on the last mentioned end of said holder, a finger grip member adjustably mounted on the other end of said holder, and means to fasten said strip at the other end to said member.

80 2. A device of the class described comprising a holder, a strip of polishing material, means to fasten said strip at one end to one end of said holder, a finger grip on the last mentioned end of said holder, a finger grip member pivotally mounted on the other end of said holder, and means to fasten said strip at the other end to said member.

85 3. A device of the class described comprising a holder having a finger grip portion at one end, a strip of polishing material, means to fasten said strip at one end to the end of said holder having said grip portion, a finger grip member adjustably mounted on the other end of said holder, and means to fasten said strip at the other end to said member, whereby when said member is moved toward said grip portion, said strip is placed under tension.

90 4. A device of the class described comprising a holder having a grip portion at one end, a strip of polishing material, means to fasten said strip at one end to the end of said holder having said grip portion, a grip member pivotally mounted on the other end of said holder, and means to fasten said strip at the other end to said member, whereby when said member is swung toward said grip portion, said strip is placed under tension.

95 5. A device of the class described comprising, a holder having a bearing surface at one end, a grip member adjustably mounted on the other end of said holder and having a bearing surface, U-shaped clamping members pivotally connected with said holder and member, respectively, so that the medial portions thereof may engage said respective bearing surfaces, and a strip of pol-

ishing material the opposite ends of which engage said respective surfaces and are passed around the medial portions of said respective clamping members, for the purpose specified.

6. A device of the class described comprising, a holder having a bearing surface at one end, a grip member pivotally mounted on the other end of said holder and having a bearing surface, U-shaped clamping members pivotally connected with said holder and member, respectively, so that the medial portions thereof may engage said respective bearing surfaces, and a strip of polishing material the opposite ends of which engage said respective surfaces and are passed around the medial portions of said respective clamping members, for the purpose specified.

7. In combination, a holder having a grip portion and a bearing surface at one end, a grip member adjustably mounted on the other end of said holder and having a bearing surface, U-shaped clamping members pivotally connected with said holder and member, respectively, so that the medial portions thereof may engage said respective bearing surfaces, and a strip of polishing material the opposite ends of which engage said respective surfaces and are passed around the medial portions of said respective clamping members, whereby when said member is moved toward said grip portion said strip is gripped and placed under tension, for the purpose specified.

8. In combination, a holder having a grip portion and a bearing surface at one end, a grip member pivotally mounted on the other end of said holder and having a bearing surface, U-shaped clamping members pivotally connected with said holder and member, respectively, so that the medial portions thereof may engage said respective bearing surfaces, and a strip of polishing material the opposite ends of which engage said respective surfaces and are passed around the medial portions of said respective clamping members, whereby when said member is swung toward said grip portion said strip is gripped and placed under tension, for the purpose specified.

9. In combination, a holder comprising two hingedly connected parts, a strip of polishing material, means to fasten said strip at one end to the free end of one of said parts, grip means provided on said last mentioned part, a grip member adjustably mounted on the free end of the other of said parts, and means to fasten said strip at the other end to said member, for the purpose specified.

10. In combination, a holder comprising two hingedly connected parts, a strip of polishing material, means to fasten said strip at one end to the free end of one of

said parts, an upwardly extending grip portion provided on and adjacent the free end of said last mentioned part, a grip member pivotally mounted on the free end of the other of said parts, and means to fasten said strip at the other end to said member, said parts being hinged so that one may be swung around adjacent the under side of said other part, whereby when said parts are in operative position and said member is swung toward said grip portion said parts are held in rigid relationship and said strip is placed under tension.

11. A device of the class described comprising a holder having a grip portion, a grip member, and a strip of polishing material extending from end to end of said holder and fastened at one end to said holder and at the other end to said member, said grip member being so arranged on said holder that upon pressing it toward said grip portion said strip is tensioned.

12. A device of the class described comprising in combination a holder, a polishing strip extending from end to end of said holder, and finger-engaging pressure means movably mounted on the holder for constantly regulating the tension of said polishing strip during its polishing operation.

13. A device of the character described comprising an elongated holder having inwardly extending end portions, a strip of yieldable polishing material adapted to project between and engage said end portions, said strip being normally out of tension, and finger-engaging means mounted on the holder end operatively associated with said strip and acting under the pressure of the finger to regulate the tension of the strip.

14. An article of the class described comprising in combination a holder, a polishing strip extending from end to end of said holder, and a finger-engaging supporting connection between said strip and holder and movable with respect to the holder for tensioning said polishing strip while in use through pressure applied by the user's hand.

15. A polishing device comprising a hand-engaging holder, the opposite ends of which project inwardly, a strip of polishing material yieldable throughout its length adapted to project between the inwardly projecting ends of the holder whereby to leave a space between the strip of polishing material and body portion of the holder, means for removably connecting the strip of material to the holder, and associated finger-engaging means movable with respect to the holder and adapted to be grasped by the operator in the use of the device whereby to regulate the yieldable characteristics of the strip without removing the hand of the operator or interrupting the operation of the device.

16. A device of the character described comprising a holder having a grip portion, a

grip member, a strip of polishing material extending from end to end of said holder and adapted to be connected adjacent one end thereof, and an operative connection between said grip member and the opposite end of said strip, said grip member being free to move whereby as the holder and grip member are grasped by the hand of the operator in the operation of the device the strip will automatically be placed under tension.

17. Polishing means comprising a strip of velvety, pliant, buffing material, and a strip of non-resilient, pliant and relatively non-stretchable fabric, one of said strips having on one side a coating of adhesive against which the other strip is pressed to unite the two strips.

18. Polishing means comprising a strip of velvety, pliant, buffing material, a strip

of non-resilient, pliant and relatively non-stretchable fabric, and means for uniting the two strips.

19. A polishing strip comprising a velvety, pliant buffering portion and a non-resilient, pliant and relatively non-stretchable fabric backing portion, said buffering and backing portions being permanently secured together.

20. A relatively thin polishing means comprising a thin surface strip of pliant buffering material, a relatively non-stretchable and non-resilient thin strip of fabric constituting a backing for the first-mentioned strip, and means for permanently uniting these strips of material together while maintaining a continuous unbroken operating surface.

PHILIP C. P. BOOTY.
